UNITED STATES PATENT OFFICE

171,303

WHEEL COVER OR SIMILAR ARTICLE

George Albert Lyon, Detroit, Mich.

Application April 17, 1953, Serial No. 24,553

Term of patent 14 years

(Cl. D14—30)

To all whom it may concern:

Be it known that I, George Albert Lyon, a citizen of the United States, and a resident of the city of Detroit, in the county of Wayne and State of Michigan, have invented a new, original, and ornamental Design for a Wheel Cover or Similar Article, of which the following is a specification, reference being had to the accompanying drawing, forming a part thereof.

On the drawing:

Figure 1 is a side elevational view of a wheel cover embodying my new design;

Figure 2 is a profile view showing the cross-sectional contour of the cover of Figure 1; and

Figure 3 is a fragmentary side perspective view of the cover.

The conventional tire and wheel assembly disclosed in dotted lines are shown only for the purpose of illustration.

I claim:

The design for a wheel cover or similar article, substantially as shown and described.

GEORGE ALBERT LYON.
